ALFRED F. STONER, OF WEST UNITY, OHIO.

Letters Patent No. 84,016, dated November 10, 1868.

IMPROVEMENT IN CULTIVATORS.

The Schedule referred to in these Letters Patent and making part of the same.

To all whom it may concern:

Be it known that I, ALFRED F. STONER, of West Unity, in the county of Williams, and State of Ohio, have invented a new and useful Improvement in Cultivators; and I do hereby declare that the following is a full and exact description thereof, reference being had to the accompanying drawings, and to the letters of reference marked thereon.

My invention consists of a peculiar construction of cultivators, provided with a novel arrangement of toothed roller and gear-wheels for pulverizing soil.

In the accompanying drawings—

Figure 1 is a top view of my improved cultivator.

Figure 2 is a longitudinal section of the same on the line *x x*; fig. 1.

The frame, A, of my cultivator is made with a bow, A', in front, in order to embrace the roller B. One share, C, is placed in the middle front of this roller, and two broad shovel-plows, D, nearly under the roller. A fourth shovel-plow is placed on the right hand of the machine, at E, fig. 1, for hilling.

The toothed roller B is set in motion by a series of gear-wheels, as follows: The wheel F travels on the ground, and sets in motion the gear-wheel G, on the same shaft or axle. The latter wheel gears into the wheel H, which, in turn, gears into wheel I, on the shaft of roller B. By this arrangement the roller B is set in motion.

Under the roller B is a toothed bar or spring-con-

cave, M, which, in connection with roller B, will pulverize the soil, tear in pieces the clods, and loosen the dirt from grass, roots, and weeds, in a thorough manner. The plate M has a rocking motion, in order to release or let pass stones or other rigid obstacles, which are liable to be caught, and might otherwise break the machine. The spring L holds the plate M with sufficient firmness to tear clods, but yields to such strain as might otherwise break the cultivator.

In the use of my machine, either the hillier E, the spiked roller, or concave, or all of them, may be removed, thus adapting the machine to different work, as may be desired.

I do not broadly claim the use of a spiked roller, or gear-wheels for operating the same.

Having thus fully described my invention,

What I claim, and desire to secure by Letters Patent of the United States, is—

1. The spiked roller B, in combination with the spring-concave or toothed bar M, arranged and operated substantially as set forth.

2. Also, the arrangement of the hillier E, in combination with the share C, in the front part of the frame, and the pulverizing-roller and concave, substantially as described.

ALFRED F. STONER.
